(57) **CLAIM**

The ornamental design for an electronic device, as shown
and described.

DESCRIPTION

FIG. 1 is a front side elevation view of an electronic device
showing the new design in a first embodiment.

FIG. 2 is a back side elevation view of FIG. 1.

FIG. 3 is a left side elevation view of FIG. 1.

FIG. 4 is a right side elevation view of FIG. 1.

FIG. 5 is a top side plan view of FIG. 1.

FIG. 6 is a bottom side plan view of FIG. 1.

FIG. 7 is a front side perspective view of FIG. 1.

FIG. 8 is a back perspective view of FIG. 1.

FIG. 9 is a front perspective view of FIG. 1.

FIG. 10 is a back top perspective view of FIG. 1.

FIG. 11 is a front side perspective view with the stand in a
first position, it being understood that all other surfaces are
the same.

FIG. 12 is a back side perspective view of FIG. 11.

FIG. 13 is a front side elevation view of the electronic device
showing the new design in a second embodiment.

FIG. 14 is a back side elevation view of FIG. 13.

FIG. 15 is a left side elevation view of FIG. 13.

FIG. 16 is a right side elevation view of FIG. 13.

FIG. 17 is a top side plan view of FIG. 13.

FIG. 18 is a bottom side plan view of FIG. 13.

FIG. 19 is a front side perspective view of FIG. 13.

FIG. 20 is a back perspective view of FIG. 13.

FIG. 21 is a front perspective view of FIG. 13.

FIG. 22 is a back top perspective view of FIG. 13.

FIG. 23 is a front side perspective view with the stand in a
first position, it being understood that all other surfaces are
the same.

FIG. 24 is a back side perspective view of FIG. 23.

FIG. 25 is a front side elevation view of the electronic device
showing the new design in a third embodiment.

FIG. 26 is a back side elevation view of FIG. 25.

FIG. 27 is a left side elevation view of FIG. 25.

FIG. 28 is a right side elevation view of FIG. 25.

FIG. 29 is a top side plan view of FIG. 25.

FIG. 30 is a bottom side plan view of FIG. 25.

FIG. 31 is a front side perspective view of FIG. 25.

(Continued)

FIG. 32 is a back perspective view of FIG. 25.
 FIG. 33 is a front perspective view of FIG. 25.
 FIG. 34 is a back top perspective view of FIG. 25.
 FIG. 35 is a front side perspective view with the stand in a first position, it being understood that all other surfaces are the same; and,
 FIG. 36 is a back side perspective view of FIG. 35.
 The broken lines shown in the drawings illustrate portions of the electronic device that form no part of the claimed design.
